WELT BUTTING MACHINE

Eric A. Holmgren, Lynn, Mass., assignor to
United Shoe Machinery Corporation, Borough
of Flemington, N. J., a corporation of New
Jersey

Application August 4, 1938, Serial No. 223,052

18 Claims. (Cl. 12—67)

This invention relates to machines for operating on shoes and is illustrated as embodied in a machine for preparing a welted shoe for the sole laying operation by trimming off or butting the ends of the welt and tacking the overlasted margin of the upper adjacent to the ends of the welt to the insole. Such a machine is illustrated, for example, in United States Letters Patent No. 1,709,347, granted April 16, 1929, upon an application of George Goddu et al. An improved machine of this type is illustrated in my copending application Serial No. 174,542, filed November 15, 1937. The machine illustrated in my copending application is provided with operating instrumentalities common to machines of this type comprising devices for supporting both end portions of a welt during the butting operation, welt butting knives, shear members or anvils against which the knives operate to butt the welt, and fastening inserting means for securing the upper in the region of the welt butts to the insole. Said machine is also provided with means for pounding and flattening the inseam substance in the region of the welt butts, and means for supporting the shoe during the pounding operation. The knives move lengthwise of the shoe to butt the welt ends which are supported on the crease finders at an inclination such that the knives make a long tapering cut through the end portions of the welt.

In operating on shoes provided with storm welts, machines of this type are required to work the butted end portions of the storm welt inwardly over the insole. The storm welt usually employed has a central longitudinal rib projecting upwardly from its upper-attaching surface and serving to close the welt crease. After butting this type of a welt the butted or skived off portion of the rib extends from the butted end of the welt in the form of a tapering tab. In order to give the shoe a finished appearance this tab must be worked in over the insole into a position in which it will be inconspicuous in the completed shoe. Machines of the type referred to have been provided with means for working the tab at the butted end of a storm welt inwardly over the insole, mechanism for this purpose being shown in United States Letters Patent No. 1,614,836, granted January 18, 1927, upon an application of George Goddu.

It is an object of the present invention to provide an improved means for working the tab at the butted end of a storm welt inwardly over the insole and with this object in view a feature of the invention consists in the provision, in a

welt butting machine, of a member, herein illustrated as a welt bender, for working a butted end portion of the welt of a welted shoe, such for example as the tab on the butted end of a storm welt, inwardly toward the middle of the shoe bottom, a crease finder for supporting the welt for the butting operation, and a carrier in which both the crease finder and the welt bender are mounted for operative movement relatively to the carrier and relatively to each other widthwise of the shoe. In the illustrated machine such movement of the crease finder serves to retract it prior to the inseam pounding operation in order to obviate the formation of an impression of the crease finder in the welt by the pounding of the inseam substance. As herein illustrated, the crease finder is advanced and retracted by the same actuator which operates the welt bender for working in the tab of the storm welt, the crease finder being operatively connected to said welt bender by a locking element during part of the operation of said bender. The butted ends of a storm welt are thin and flimsy and present little substance for the welt bender to operate upon. Unless the welt ends are held against movement upwardly away from the shoe bottom the welt bender, instead of working the welt end inwardly as intended, merely lifts the welt end and moves inwardly between the welt end and the upper without performing its intended operation. In accordance with a feature of the invention the illustrated machine is provided with means for holding the welt end against movement away from the shoe bottom during the operation of the welt bender and thereafter until the welt end is secured to the shoe bottom. As herein illustrated, the welt end is held against movement away from the shoe bottom by the nozzle through which fastenings are driven to secure the welt end to the shoe bottom. To this end the nozzle is brought into a position adjacent to the top of the welt end prior to the operation of the welt bender.

It is the usual practice in butting welts on welt butting machines of the illustrated type, to position the shoe lengthwise thereof by bringing the end stitch at each side of the inseam against the cutting edges of the anvils. In operating on different types of shoes it is often desirable to change the position of the anvils lengthwise of the shoe in order to vary the position of the shoe relatively to the welt butting knives. For example, in operating on women's high-heeled shoes it has been found desirable to adjust the anvils forwardly toward the toe end of the shoe.

in order that the welt butting knives in the course of their movement toward the toe end of the shoe will not strike the shank portion of the shoe bottom. It will be understood that in 5 changing the position of the shoe relatively to the knives the relation of the shoe to the fastening inserting means is correspondingly altered. It is an object of the present invention to provide a machine organization which permits an adjustment of the fastening inserting means similar to said adjustment of the anvils whereby the fastenings may be located in any 10 desired position lengthwise of the shoe regardless of the position of the anvils.

15 With the above object in view, a feature of the invention consists in the provision in a welt butting machine having welt butting anvils which are adjustable lengthwise of the shoe, of fastening inserting means for securing those portions 20 of the shoe upper margin in the regions of the welt butts to the shoe bottom, and means for adjusting the fastening inserting means lengthwise of the shoe.

In the illustrated machine the shoe is located 25 heightwise thereof relatively to the operating instrumentalities by moving the shoe upwardly into engagement with a holdown member, such upward movement being effected by elevating the shoe supporting member. It has been found desirable that the holdown member be located away from its operative position when the machine is at rest and remote from the path of movement of the shoe as it is introduced into the machine in order to facilitate the positioning of 30 the shoe. Accordingly, the illustrated machine is provided with means for automatically moving the holdown into a remote position to facilitate the introduction of a shoe into the machine. As herein illustrated, the holdown is moved into 40 its remote position by the operation of a toggle which, in its straightened position, holds the holdown against upward movement.

Other features of the invention relate to novel 45 means for retracting the welt butting anvils into positions remote from the shoe bottom in order to provide clearance on the shoe bottom for the operation of the fastening inserting means, and novel fastening receiving nozzles constructed and arranged to facilitate removal of fastenings which have become fouled therein.

50 These and other features of the invention will now be described with reference to the accompanying drawings and will be pointed out in the appended claims.

55 In the drawings:

Fig. 1 is a side elevation of the head of a machine embodying my invention with parts broken away to show certain details of the organization of the machine;

60 Fig. 2 is a plan view illustrating the anvil, the welt bender and the crease finder at the left of the machine as they are located when the machine is at rest, and the head in which said parts are mounted, part of the head being broken away 65 to show part of the mechanism for operating the welt bender;

Fig. 3 is a plan view similar to Fig. 2 showing the parts at a different stage in the operation of the machine and showing also part of the rear portion of a shoe in the machine;

70 Fig. 4 is a plan view similar to Fig. 2 showing the parts in their position when the tack is driven;

Fig. 5 is a sectional view taken substantially on the line V—V of Fig. 2;

75 Fig. 6 is a sectional plan view taken substan-

tially on the line VI—VI of Fig. 7, certain parts being broken to show underlying parts;

Fig. 7 is a sectional elevation taken substantially on the line VII—VII of Fig. 6;

Fig. 8 is a sectional plan view taken substantially on the line VIII—VIII of Fig. 9;

Fig. 9 is a front elevation illustrating the tack driving assembly at the left of the machine;

Fig. 10 is a detail view illustrating one of the tack receiving nozzles;

Fig. 11 is a sectional view taken substantially on the line XI—XI of Fig. 10;

Fig. 12 is a sectional elevation through the rear portion of a shoe in the machine showing the operating parts in their position after the welt 15 is butted and before the tack is driven; and

Fig. 13 is a plan view illustrating the rear portion of a shoe in the machine after the operations performed thereon by the illustrated machine have been completed.

The illustrated machine is provided with operating instrumentalities common to machines of this type comprising crease finders which support the end portions of the welt for the butting operation, welt butting knives which move lengthwise of the shoe toward its heel end making a long tapering cut to trim off the waste ends of the welt, and shear members or anvils which cooperate with the knives to complete the butting of the welt by a shearing action which produces a substantially square welt end. For securing the overlasted margin of the upper in the region of the butted ends of the welt to the insole, the illustrated machine is provided with tack driving mechanism which is similar in its construction and operation to the tack driving mechanism of the machine illustrated in my copending application above referred to. The illustrated tack driving mechanism drives one tack at each side of the shoe in a location selected by the operator and exerts a pounding action against the inseam substance in the region of the butted ends of the welt in order to flatten the end portions of the inseam rib against the insole.

Referring now to Fig. 1, the shoe is held against downward movement during the pounding operation by a jack or spindle 20 which is moved upwardly against the cone of the last before the pounding operation takes place. For cooperating with the jack 20 to hold the shoe in position for

the pounding operation, a holdown is constructed and arranged to engage the shank portion of the shoe bottom. The jack urges the shoe upwardly against the holdown, the holdown serving to locate the shoe heightwise thereof. As illustrated in Fig. 1, the holdown comprises a sliding rod 22 mounted in forward extensions 24 of the machine head and a shoe-engaging foot 26 secured to the lower end of the rod 22 and arranged to engage the heel seat portion of the shoe bottom.

Secured to a bracket 28 on the rod 22 is a shank-engaging foot 30 which is positioned heightwise of the shoe by adjusting nuts 32 on a threaded stem 34 extending upwardly from the foot 30. The shank-engaging foot 30 is spaced from the heel seat engaging foot 26 by a link 36. The holdown is moved vertically toward and from its operating position by the operation of a toggle comprising links 38 and 40 which connect the upper end of the slide rod 22 to a fixed bracket

42. When the machine is at rest the holdown is elevated as shown in Fig. 1 in order to facilitate the introduction of the shoe into the machine. At an early stage in the operation of the machine the toggle is straightened to move the

70 holdown vertically toward the shoe bottom. The holdown is moved vertically toward the shoe bottom by the operation of the toggle comprising links 38 and 40 which connect the upper end of the slide rod 22 to a fixed bracket

42. When the machine is at rest the holdown is elevated as shown in Fig. 1 in order to facilitate the introduction of the shoe into the machine. At an early stage in the operation of the machine the toggle is straightened to move the

75

holddown downwardly into its operating position by the upward movement of a cam lever 44 which is fulcrumed at 46 and is operated by a cam on the cam shaft 48. At its forward end the cam lever 44 is provided with a head 50 having a cam face which during the upward movement of the head operates a lever 52 to straighten the toggle, said lever being fulcrumed at 54 and connected to the upper toggle link 38 by a link 56. After the operations upon the shoe have been completed, the cam lever 44 returns to its initial position, illustrated in Fig. 1, and a spring pressed plunger 58 moves the lever 52 to the left as seen in Fig. 1, thus bending the toggle and lifting the holddown to its rest position.

In operating on shoes provided with storm welts, the illustrated machine is provided with two welt benders or fingers one of which is illustrated at 66 (Fig. 3) constructed and arranged to operate on the butted end of the welt to work it inwardly toward the center of the shoe bottom. The butting of a storm welt, such as the welt 64 in Fig. 3, forms a tab 62 at each end of the welt. The tab 62 is an extension of the rib of the storm welt which rib extends downwardly from the body portion of the welt. It will be seen that the finger 60 engages the tab 62 and also that portion of the welt rib adjacent to the tab. The finger 60 is moved to the right, as seen in Fig. 3, after the welt has been butted to bend the butted end inwardly toward the center of the shoe bottom and the finger holds the welt butt in this position during the tacking operation. Preferably, the tack driver is so adjusted that the tack is driven through the tab 62 to hold the welt butt in the position in which the finger 60 locates it. The welt engaging finger 60 is removably secured to a slide 66 (Fig. 12) which is mounted in a head 68 (Figs. 1, 2 and 12) for movement widthwise of the shoe. As illustrated in Fig. 1, the head 68 is mounted on a bracket 70 which is fulcrumed at 72 for swinging movement toward and from the shoe. It will be understood that another head like the head 68, having a welt engaging finger corresponding to the finger 60 is provided at the right side of the machine. For simultaneously operating the welt engaging fingers, the illustrated machine is provided with a lever 74 (Fig. 1) secured to a rockshaft 76 and operated by a cam on the cam shaft 48. At each end of the rockshaft 76 there is secured a short arm having a beveled gear segment formed therein. The short arm at the left of the machine is illustrated at 78 in Fig. 1 together with the train of mechanism through which said arm operates the slide 66. It will be understood that a corresponding arm and train of mechanism are provided at the opposite side of the machine for operating the slide at the right of the shoe. The gear segment at the end of the short arm 78 meshes with a beveled gear 80 at the rear end of a rockshaft 82. The rockshaft 82 has a universal connection to a sleeve 84 which is fluted for the reception of a shaft 86 the rear portion of which is provided with longitudinal teeth 88 which slide in the flutings in the sleeve 84 and provide a connection whereby the rotation of the sleeve is imparted to the shaft. It will be understood that this construction permits adjustment of the head 68 in the direction of the length of the shaft 86. At its forward end the shaft 86 has a universal connection to a rockshaft 90 mounted in bearings in the bracket 70. Secured to the rockshaft 90 is an arm 92 (Figs. 1 and 2) which carries at its upper end a short shaft 93

having at its forward end a roll 94 which is positioned in a square cut notch 96 in the slide 66.

The butted end of the storm welt 64 is relatively thin and the operation of the finger 60 tends to cause the finger to lift the welt end and pass under it without bending it inwardly. To counteract this tendency the welt end is held against upward movement by a tack nozzle 171 (Fig. 9) which is moved downwardly prior to the operation of the finger 60 into a position in which it holds the welt end against upward movement but does not press against it or in any way interfere with the bending of the welt end inwardly toward the center of the shoe bottom by the operation of the finger 60.

Also mounted in the head 68 is a slide 95 (Fig. 2) which carries a welt butting anvil 97 and a slide 98 which carries a crease finder 100. During the welt butting operation, the crease finder is positioned in the welt crease as illustrated in Figs. 3 and 12. After the welt has been butted and before the pounding operation occurs, the crease finder is withdrawn from the welt crease in order that no imprint thereof will be formed in the welt in the pounding operation. For advancing the crease finder into the welt crease and withdrawing it therefrom the crease finder slide 98 is provided with a connection to the slide 66 comprising a ball 102 which is mounted in a hole provided in the slide 98 and is arranged to enter a socket 104 in the slide 66. In the operation of the machine the welt engaging finger 60 operates after the crease finder has come to the limit of its advancement and the illustrated construction is such that the ball 102 is removed from the socket in the slide 66 when the crease finder comes to the end of its advancement in order to permit further advancement of the slide 66 independently of the crease finder slide 98. During its operative movement, the finger 60 moves from its position in Fig. 2 into its position in Fig. 3 bending the welt end inwardly into the position in which it is shown in Fig. 3. While the finger is in this position the tacker (hereinafter described) is pressed against the welt end to hold it in the position into which it is brought by the finger whereupon the finger is withdrawn into its position in Fig. 4. During the withdrawal of the finger 60 the socket 104 in the slide 66 comes into position to receive the ball 102 and simultaneously an upward extension 112 (Fig. 12) of the slide 66 engages the end wall 114 of a recess in the crease finder slide. As the slide 66 continues to retract it carries the crease finder slide with it and causes the ball 102 to be transferred from its position in Fig. 2 to its position in Fig. 4. The ball 102 serves to lock the slide 66 to the crease finder slide 98 during the remaining portion of the retracting movement of the finger 60 and also during part of the advancement of the finger 60 from its position in Fig. 2 into its rest position in Fig. 2 which occurs between the tacking operation and the end of the machine cycle. During the advancement of the slide 66 a stop 110 at the outer end of the crease finder slide 98 engages the head 68 (Fig. 2) and prevents further advancement of said slide. As the slide 66 continues to advance, the ball 102 is cammed forwardly by the outer wall of the socket 104 in the slide 66 and seated in a socket 108 in the head. In this position the ball is confined by the slide 66 as said slide continues and completes its operative movement. In this position the ball 102 locks the crease finder slide 98 with the crease finder in its advanced position and the slide 98

remains thus locked until the slide 66 is again retracted.

For retracting the welt butting anvils in order to permit tacks to be driven through those portions of the over-lasting margin of the upper which are covered by the anvils during the welt butting operation, the illustrated machine is provided with a cam lever 116 (Fig. 1) fulcrumed at 118 to the machine head and operated by a cam 5 on the shaft 48. The lever 116 operates a slide 120 (Fig. 6) provided at its forward portion with a transverse groove 122 (Fig. 7) in which are mounted blocks 124 swiveled on the heads of screws 126 carried by inward extensions of slides 15 128 mounted in guideways in swinging brackets 148. The anvils 97 are retracted by novel mechanism operated by the slides 128 comprising levers 132 (Fig. 6) which are fulcrumed at 134 on the brackets 70 and are provided at their forward ends with rolls 136 which operate in slots 138 in the slides 95 which carry the anvils. Projecting outwardly from the slides 128 are arms 142 which carry at their outer ends rolls 144 which, as illustrated in Fig. 6, operate in cam 20 grooves 146 in the anvil retracting levers 132. As in the machine illustrated in my copending application the slides 128 carry welt butting knives 147. The knives are operated during the first part of the operative movement of the slides 30 128 which is a movement to the right as seen in Fig. 6. During the welt butting operation the rolls 144 move idly through the forward portions of the grooves 146 and after the welt has been butted said rolls operate in the outwardly extending portions of said grooves thus operating the levers 132 to retract the anvils.

The illustrated tack driving mechanism is in most respects similar in its construction and operation to the tack driving mechanism illustrated and described in my copending application above referred to. Referring to Fig. 8, the tack driving mechanism at the left of the machine is mounted on the bracket 148 which swings on a vertical shaft 150 in the machine head and 40 is provided with a guideway 152 which, as illustrated in Fig. 9, extends diagonally downward and toward the center of the machine. Mounted in the guideway 152 is a slide 154 having a long hub 156 (Fig. 8) on which is slidably mounted a sleeve 158 to which is secured a front plate 160. Two horizontal keys 162 are secured to the front plate 160 and are mounted in grooves 164 in a slide 166 which is confined between the front plate 160 and flanges 168 which extend outwardly 50 from the rear portion of the sleeve 158. The slide 166 has a round opening 167 through which extends the sleeve 158 and this opening is large enough to permit horizontal adjustment of the slide. The slide 166 carries a sliding member 170 in which is incorporated a tack receiving nozzle 171 (Fig. 9). For adjusting the slide 166 generally widthwise of the shoe, a hand screw 174 (Fig. 8) is threaded into a tapped hole in the head of a pin 176 in the slide 166 and is journaled 60 in a bearing in a bracket 178 extending outwardly and upwardly from the front plate 160. The screw 174 is held against endwise movement in the bracket by a collar 180 and a shouldered portion 182 of said screw. For adjusting the slide 65 166 generally lengthwise of the shoe a hand screw 184 is threaded into a tapped hole in the center of the hub 156 of the slide 154 and is held against longitudinal movement relative to the front plate 160 by a collar 186 and the shouldered forward portion 88 of the hand screw. It will be seen

that in adjusting the tacker widthwise of the shoe the slide 166 moves in a path extending at right angles to the hand screw 184 between the front plate 160 and the flanges 168 of the sleeve 158, while in the adjustment of the tacker lengthwise of the shoe the sleeve 158 together with the front plate 160 and the slide 166 move as a unit longitudinally of the hub 156 of the slide 154. For holding the tacker assembly against turning movement about the hub 156, the sleeve 158 has 10 an upward extension 190 (Fig. 9) which is slidably mounted between the inner walls of forward extensions 192 of the slide 154. For operating the tack driving pin 172 the illustrated machine is provided with mechanism similar to that disclosed in my copending application comprising a compression spring 194 mounted in a barrel 196 on the slide 166. The spring imparts upward pressure to the outer end of a lever 198 fulcrumed at 200 on the slide 166. The lever 198 20 operates a slide 202 which is carried by the member 170 and has mounted in its lower portion the tack driving pin 172. The spring 194 operates in the course of the downward movement of the slide 154 upon the withdrawal of a latch member 204 which engages the outer end of the lever 198. The latch member is fulcrumed at 203 on the slide 166 and has an angular extension 208 which, in the course of the downward movement of the tacker assembly, engages a tripping pin 210 on the bracket 148 and causes the latch member 204 to be disengaged from the lever 198. The slide 154 is moved downwardly by the operation of the cam lever 44 (Fig. 1) which operates the hold-down. The lever 44 operates a slide 212 (Fig. 9) 30 on the shaft 158 which in turn operates a lever 214 fulcrumed at 216 on the bracket 148 and connected by a link 218 to the slide 154.

The illustrated machine is provided with tack nozzles one of which is illustrated in Fig. 10. Said nozzle comprises a pair of headed plugs 220 which are mounted in a cross bore 222 in the lower end portion of the member 170 and meet at the center of said bore. The inner end face of each of the plugs 220 has a recess 224 providing half of a tack receiving pocket into which tacks are delivered through a tube 226 (Fig. 9). For holding said tack pocket in tack receiving position each plug 220 has a longitudinal groove 228 into which projects the end of a pin (not shown) mounted in the member 170. The plugs 220 are positioned longitudinally of the bore 222 by two leaf springs 232 which hold the inner end faces of the plugs against each other under light pressure. The lower portion of each spring 232 45 has a V-shaped offset 234 which is seated in an end groove in one of the plugs 220 and at its upper end each of the springs has a similar V-shaped offset 236 which is seated in a suitable recess in the member 170 thus holding the spring 50 against movement longitudinally of said member. Each spring 232 is held in position by a T-shaped pin 238 (Fig. 11) which is pinned in a socket in the member 170 and extends through a slot 240 in the spring and is secured to said member. 55 Whenever a tack becomes fouled in the tack pocket it may readily be extricated by a small screw driver or similar tool after first removing one of the plugs 220. The illustrated construction permits either plug to be removed readily, 60 each of the illustrated springs 232 being readily movable upwardly into a position in which its lower end is out of engagement with the end face of the plug. To this end each spring has a finger grip 241 (Fig. 10) at its upper end. To 65 70 75

facilitate its removal each plug 220 is provided near its outer end with a peripheral groove 242 into which a screw driver may be inserted. As a tack is driven the plugs 220 move way from each other to permit the head of the tack and the driving pin to move downwardly between them.

The operation of the illustrated machine is the same in most respects as the operation of the machine illustrated in my copending application, 10 above referred to. The operation of the machine will be briefly described with reference to the butting of storm welts of the type herein illustrated and described. It will be understood that in operating on other types of shoes the welt 15 benders 60 are removed and the crease finders for storm welt work are replaced by other crease finders suited to the type of shoe to be operated upon, the actual cycle of the machine remaining unchanged. The operation is as follows: A shoe 20 held by the operator in inverted position is moved heel foremost into the machine and is located lengthwise thereof by bringing the end stitch of the inseam on each side of the shoe against the cutting edge of the anvil. The shoe is so 25 positioned heightwise thereof that the crease finders locate in the welt crease. The welt benders are arranged as seen in Fig. 2, when the machine is at rest and they too are located in the welt crease as the shoe is brought into position 30 to be operated upon. After the shoe is thus positioned, the machine is set in motion, whereupon the shoe is gripped between the holdown 26 and the last engaging spindle 20. The knives 147 then operate to butt the welt, then the anvils 35 97 move outwardly away from the shoe bottom. The tack nozzles then move downwardly into a position adjacent to the upper surfaces of the welt ends. The welt benders then operate to work the welt ends inwardly over the shoe bottom, 40 whereupon the tack nozzles again move downwardly and grip the welt ends against the shoe bottom to hold them in the position into which the welt benders have brought them. The crease finders and the welt benders are then withdrawn 45 from the welt crease, whereupon the tacks are driven, completing the operations on the shoe. Preferably, tack drivers are so adjusted that the tacks are driven through the welt tabs, the overlasted margin of the upper, the flange of the 50 counter wings and the insole and are clenched against the inner surface of the insole.

Having thus described my invention, what I claim as new and desire to secure by Letters 55 Patent of the United States is:

1. In a welt butting machine, a member for working a butted end portion of the welt of a welted shoe inwardly toward the middle of the shoe bottom, a crease finder, and a carrier in which both the crease finder and said member are mounted for operative movement relatively to the carrier and relatively to each other widthwise of the shoe.

2. In a welt butting machine, a member for working a butted end of the welt of a welted shoe inwardly toward the middle of the shoe bottom, a crease finder, an actuator for said member, and means whereby the crease finder derives its operative movement from the operative movement of said member.

3. In a welt butting machine, a member for working a butted end of the welt of a welted shoe inwardly toward the middle of the shoe bottom, a crease finder, a carrier in which both the crease finder and said member are mounted for

operative movement relatively to the carrier widthwise of the shoe, an actuator for said member, and means for locking said member to the crease finder in order that the operative movement of said member will be imparted to the 5 crease finder.

4. In a welt butting machine, a member for working a butted end of the welt of a welted shoe inwardly toward the middle of the shoe bottom, a crease finder, a carrier in which both the crease 10 finder and said member are mounted for operative movement relatively to the carrier widthwise of the shoe, and a locking element carried by the crease finder and transferable from a position in which it locks the crease finder to said member 15 into a position in which it locks the crease finder to the carrier.

5. In a welt butting machine, a member for working a butted end of the welt of a welted shoe inwardly toward the middle of the shoe bottom, a carrier in which said member is slidably mounted for movement widthwise of the shoe, a crease finder slidably mounted in the carrier between said member and a wall of the carrier, a locking element carried by the crease finder and 20 arranged to be positioned alternatively in a recess in said member and a recess in the carrier, means for arresting the advancement of the crease finder when the locking element registers with the recess in the carrier, and a lug on said member constructed and arranged to engage the crease finder at that stage in the retraction of 25 said member when the recess provided therein registers with said locking element.

6. In a welt butting machine for operating on 30 shoes provided with that type of welt having a longitudinal rib projecting from its upper attaching surface, the combination with instrumentalities for butting the welt of a member for working the butted end portion of the welt rib 40 inwardly toward the center of the shoe bottom, and means for holding the end portion of the welt rib against movement away from the shoe bottom during the operation of said member and thereafter until the butted end portion of the welt rib 45 is secured to the shoe bottom.

7. In a welt butting machine for operating on 50 shoes provided with that type of welt having a longitudinal rib projecting from its upper attaching surface, the combination with instrumentalities for butting the welt of a welt bender for working the butted end portion of the welt rib inwardly toward the center of the shoe bottom, fastening-inserting means including a member through which a fastening is driven to secure the butted end portion of the welt rib to the shoe bottom, and means for bringing said member into a position in which it overlies the butted end portion of the welt rib and holds said end portion against movement away from the shoe 60 bottom during the operation of the welt bender and thereafter until said end portion is fastened to the shoe bottom.

8. In a welt butting machine for operating on 65 shoes provided with that type of welt having a longitudinal rib projecting from its upper attaching surface, the combination with instrumentalities for butting the welt of a welt bender constructed and arranged for movement generally widthwise of a shoe in the machine to force 70 the butted end portion of the welt rib inwardly toward the center of the shoe bottom, means for fastening said end portion to the shoe bottom including a nozzle through which fastenings are driven, and means operating prior to the opera- 75

tion of the welt bender to move said nozzle into a position in which it overlies the butted end portion of the welt rib and holds said end portion against movement away from the shoe bottom without interfering with the inward movement of said end portion by the welt bender.

5 9. In a welt butting machine, the combination with welt butting knives for simultaneously removing both waste ends of the welt of a welted 10 shoe, and shear members against which the knives operate, of a carrier for each knife, an actuator for the carriers, a cam for operating the actuator, and means operated by the advancement of the carriers after the welt has been butted for 15 retracting the shear members into positions remote from the shoe bottom.

10 10. In a welt butting machine, the combination with welt butting knives and anvils against which the knives operate to shear off the waste 20 ends of the welt of a welted shoe, of a carrier for each anvil adjustable lengthwise of a shoe in the machine, fastening-inserting means for securing those portions of the shoe upper margin in the regions of the welt butts to the shoe 25 bottom, and means for adjusting the fastening-inserting means lengthwise of the shoe to position it relatively to the anvil.

11. In a welt butting machine, the combination with welt supporting means and a welt butting shear member, of a carrier for both said 30 welt supporting means and said shear member adjustable lengthwise of a shoe in the machine, fastening-inserting means for securing those portions of the shoe upper margin in the regions 35 of the welt butts to the shoe bottom, and means for adjusting the fastening-inserting means lengthwise of the shoe to position it relatively to said welt supporting means and said shear member.

40 12. In a shoe machine, the combination with fastening-inserting mechanism comprising a frame constructed and arranged to swing on a vertical axis, and a slide mounted on the frame for up and down movement, of a carrier on the 45 slide, fastening-inserting means mounted on the carrier, means for adjusting the carrier widthwise of a shoe in the machine, and means for adjusting the carrier lengthwise of the shoe.

13. In a shoe machine, the combination with 50 a frame constructed and arranged for swinging movement about a vertical axis, and a slide mounted on the frame for movement downwardly and inwardly toward a vertical plane common to the longitudinal median line of the rear part of a shoe in the machine, of a carrier mounted on the slide, fastening-inserting means mounted on the carrier, means for adjusting the carrier widthwise of the shoe, and means for adjusting the carrier lengthwise of the shoe.

55 14. In a shoe machine, the combination with 60 a frame constructed and arranged for swinging movement about a vertical axis and a slide mounted on the frame for rectilinear movement downwardly and toward a plane common to the longitudinal median line of the rear part of a

shoe in the machine, of a carrier mounted on the slide for movement both widthwise and lengthwise of a shoe in the machine, fastening-inserting means mounted on the carrier, an adjustor for moving the carrier widthwise of the shoe, and another adjustor for moving the carrier lengthwise of the shoe.

5 15. In a machine for operating on shoes in which a welt together with the overlasted margin of an upper are secured to a sewing rib of 10 an insole by an inseam, the combination with means for pounding the upstanding substance secured by the inseam inwardly and downwardly against the insole, of a holdown constructed and arranged to engage the shoe bottom, means for 15 pressing the shoe upwardly against the holdown and sustaining it during the pounding operation, and power-operated means for moving the holdown into a remote position facilitate 20 the introduction of a shoe into the machine.

16. In a machine for operating on shoes in which a welt together with the overlasted margin of an upper are secured to a sewing rib of 25 an insole by an inseam, the combination with means for pounding the upstanding substance secured by the inseam inwardly and downwardly against the insole, of a holdown constructed and arranged to engage the shoe bottom, means for 30 pressing the shoe upwardly against the holdown and sustaining it during the pounding operation, and means operating automatically after the pounding operation to lift the holdown into a remote position to facilitate the removal of the shoe and the introduction into the machine of another shoe to be operated upon.

35 17. In a shoe machine, the combination with means for applying pressure to the bottom of a shoe in the machine, of a holdown constructed and arranged to engage the shoe bottom, means for pressing the shoe upwardly against the holdown and sustaining it during the application of pressure to the shoe bottom, said holdown being movable upwardly away from the shoe bottom to facilitate the removal of the shoe from the machine, and means for operating the holdown 40 including a toggle which in its straightened position prevents upward movement of the holdown from its operative position.

45 18. In a shoe machine having fastening-inserting means, a nozzle through which fastenings are driven comprising a pair of abutting plugs constructed and arranged to receive a fastening between them, a member in which said plugs are mounted and from which one of said plugs is removable bodily to permit access to a 50 tack positioned between them, means for holding said removable plug in operative position comprising a spring carried by said member and movable in the direction in which fastenings are driven into a position in which it does not oppose removal of said removable plug from the member, and pin and slot connections for permanently attaching the spring to the member while permitting such movement of the spring.

60 ERIC A. HOLMGREN.
